COLOR FACSIMILE RECEIVER

La Verne R. Philpott, Washington, D. C., assignor
to Finch Telecommunications, Inc., Passaic,
N. J., a corporation of Delaware

Application July 11, 1945, Serial No. 604,379

28 Claims. (Cl. 178—5.4)

1

My present invention relates to facsimile receivers, and more particularly to a facsimile receiver using a plurality of colored pencils to record a colored image on the recording sheet fastened around the drum of the facsimile receiver.

Essentially my invention utilizes the basic principle of a recording pencil as disclosed in the application of La Verne R. Philpott for Facsimile recording systems, Serial No. 567,022, filed December 7, 1944.

In the present case, however, the apparatus is specifically adapted for the recording of a plurality of colors with means for distinguishing among the various recording media in order to predetermine the particular color which is to be recorded at any instant.

Heretofore in the transmission of color pictures by facsimile, it has been necessary to separate the colors of the transmitted image at each specific area into its elemental colors. This has commonly been done by the rotation of a disk in front of the optical system of the transmitting mechanism, the said disk having various color filtering elements.

As shown in Patent Nos. 2,185,806 and 2,177,247, the signals received successively through the color filters were then transmitted and received on a recording device or plurality of recording devices adapted to form color separation negatives, that is, each elemental color was recorded on a separate negative and then the three or more negatives, or the prints therefrom, were laid together to form a composite picture.

A specific object of my invention is the direct recording of a color picture at a facsimile receiver on a single recording sheet.

Another object of my invention is the formation of a color facsimile record by a receiver, which record requires no further processing of any kind in order to be usable as a color picture.

Another object of my invention is the utilization of a plurality of colored pencils or markers at a facsimile receiver in order to form a color facsimile thereat.

These and many other objects of my invention will become apparent in the following description and drawings in which

Figure 1 is a general view partly broken away of my novel facsimile recorder.

Figure 2 is a cross-sectional view showing the

2

operation of one of the recording units or pencil motors of Figure 1.

Figure 3 is an exploded view of a portion of the lead feed mechanism of Figure 2.

5 Figure 4 is an exploded view of another portion of the lead feed mechanism which cooperates with the members of Figure 3.

Figure 5 is a cross-sectional view showing the detailed operation of the lower portion of the recorder of Figure 1.

Figure 6 is a side view of the armature shell 270 of the printing motor of Figure 2 showing the suspension means therefor.

Figure 7 is an end view taken from line 7—7 of Figure 6.

Figure 8 is a top view of the printing motors assembly taken from line 8—8 of Figure 1.

Figure 9 is a top view partly in cross-section of a paper feed device adapted for the present invention.

20 Figure 10 is a cross-sectional view of the drum 11 of Figure 1 showing the paper clamp and operation thereof.

Figure 11 is a schematic view showing the operation of the control mechanism.

Referring now to Figure 1, the facsimile recorder 10 comprises a picture carrying drum 11 around which is fastened a plain white recording sheet, the fastening being accomplished in a manner specifically hereinafter described.

For optimum operation, the drum 11 is driven vertically in order to prevent variations in the pressure of the color pencils due to gravity which might possibly occur were the drum driven horizontally. The drum 11 is driven longitudinally of its axis by the screw thread 12 and is prevented from rotating during printing by the concentric splined shaft 13 cooperating with the splined nut 14 extending upwardly from the drum 11 and down through the center of screw 12.

40 Gear 20 is fastened to the bottom of the splined shaft 13 and, as seen in Figure 5, meshes with the spring loaded gear segment 95 (see also Figure 5) which is rotatably mounted on the post 22.

The gear segment 95 is biased by tension spring 23 so that the stop 24 extending from the lower face of gear 95 is moved into engagement with the stationary stop 25. Accordingly the gear 20 45 is normally held fixed by gear 95 and the bias

spring 23 and stops 24 and 25 which co-act therewith.

Gear 20, as noted above, is connected to the lower end of the splined shaft 13 which end of the shaft extends concentrically through a longitudinal opening in the threaded shaft 12. Thus, as the drum 11 is moved vertically upward by rotation of the threaded shaft 12, the near side of shaft 12 moving toward the right with respect to Figure 1, the splined shaft 13 is held stationary by the engagement of its gear 20 with the stopped gear 95, which in turn is held in place as above described by spring 23 and stops 24 and 25.

As will be clear, at the initiation of the operation of recording, drum 11 is at the bottom of cylinder 30 with the upper end 31 of the drum 11 being located substantially in the area of the pencil motors 32, 32. Recording thus starts at the area 31 of drum 11 and as the drum 11 is moved upwardly without rotation thereof, the rotation of motors 32, 32 thereabout results in helical scanning. The cylinder 30 is rotatably mounted on thrust bearing 33 so that it is free to rotate with respect to the drum 11 and is driven from shaft 51 of motor 50, which shaft is connected by a suitable gear to gear 30a mounted on the neck of cylinder 30.

At its upper end the rotatable cylinder 30 carries an annular horizontal plate 36 which carries the pencil motors 32, 32. An upper stationary cylinder 35 is provided secured in any suitable manner as by bolts 38, 38, to the main frame or housing 40 of the receiver 10. The said cylinder 35 serves to protect the drum 11 as it moves upwardly during recording.

Preferably plate 36 carries four printing motors 32, carrying respectively red, yellow, blue and black colored pencil leads, each lead being about .037" in diameter and about 4" long. Each motor is so aligned with respect to the other motors that as the cylinder 30 rotates, its mark is superimposed upon that made by the motor immediately ahead of it with the exception of one. Each pencil is stepped up one quarter of the pitch so that as the drum moves up, the lines are superimposed.

An alternative arrangement may be used where all the pencil motors were aligned so that their axes all lay in the same equatorial plane about the axis of cylinder 11 so that no color would superimpose upon another, but lay side by side on separate interleaved helices upon the record as cylinder 11 moves continuously upward. This method may, however, require the use of a different system of recording primary colors than that imposed by the direct superposition of pigments. This modified system of color deposition may, however, reduce the color smearing since each color prints on unmarked paper rather than partly on a location at which another color had been previously placed.

My device may also be adjusted so that the successive colors partially overlap. After a cycle of printing of all the color in succession, the drum has advanced one pitch in printing. In this case all pencils will be in the same equatorial plane.

Each motor 32 operates in a manner described in the above mentioned application Serial No. 567,022. Each motor is provided with armature means hereinafter more specifically described for causing its pencil to move into greater or lesser pressure engagement with the sheet in accordance with the received impulses. These armatures are

connected respectively through the four slip rings 263 (Figure 2) either by wire or by an appropriate radio circuit to an amplifier in a transmitter of the type generally described in Patent No. 2,177,247.

In the transmitter, however, the printing motor is replaced by an optical system and photoelectric cell pick-up device conventionally designed. Scanning is done at the transmitter by a minute circle of light at each position so that the photocell which responds for any color is illuminated by a complementary color. In this manner the failure of illumination in the complementary color means absorption of light by the desired color which is momentarily under the view of the scanning spot. The degree of failure of this supplementary color causes the printing motor for that color to print at the recorder. Thus, if an area being scanned is white, both the desired and supplementary colors will be present and the receiver motor does not print, and that particular area at the receiver will be left white.

The pick-up at the transmitter for black might be actuated not by white light but by a combination of the lighter or warmer colors such as red and yellow, so that no black is printed until a dark shade presents itself.

The specific operation of the printing motor will be hereinafter described.

As the cylinder 30 rotates, the drum 11 is rising so as to make about one hundred printed lines to the inch. This value is adjustable by the stop screw 115 of Figure 5 as hereinafter pointed out.

In Figure 5, taken in connection with Figure 1, I have shown the mechanism for effecting in a simple manner the desired motions of the drum 11. The driving motor 50 operates the drive shaft 51 in any suitable manner and through any suitable gear reduction that may be required for the specific purpose. Drive shaft 51 is connected to gear 30a to drive cylinder 30 as above described.

Drive shaft 51 is also connected in any suitable manner as by the gear box 53 to the shaft 54 which is driven at reduced speed. Shaft 54 drives the gear 56 through the speed and direction changing mechanism 57. As seen in Figure 5, shaft 54 is connected to and drives the disk 60 within the housing 61 of the speed and direction changing mechanism 57. The disk 60 is pressed against the ball 63 by the spring washer 62 and the ball 63 is hence driven against the rotatable cylinder 64, which rotates in bearings 65, 65 in the housing 61. Suitable power transmitting pressure is obtained between disk 60, ball 63 and cylinder 64 by mounting the disk 60 rigidly to shaft 54 and placing spring washer 62 between the rear wall of the housing 61 and a suitable thrust bearing 71 at the back of the disk 60. Shaft 54 has sufficient freedom of end motion in housing 61 to permit pressure being applied to ball 63.

The drive 57 is thus of the type in which the shaft 54 drives the cylinder 64 at a speed and direction depending on the position of the ball 63 between the disk 60 and the cylinder 64. If the diameter of ball 63 is aligned with the axis of shaft 54, the ratio of the gear is effectively infinite and cylinder 64 does not rotate. If the ball 63 is above the axis of shaft 54, then the gear 56 which is connected to the threaded shaft 12 is driven so as to raise the drum 11; and if the ball 63 is below the axis of shaft 54 then

the driven gear 56 connected to the threaded shaft 12 is rotated to lower the drum 11.

It will be clear from Figure 5 that the driven cylinder 64 is connected by gear 72 and idler 73 to the driven gear 56 secured to the threaded shaft 12. The ball 63 is constrained within the roller centering yoke 75 which is arranged to move the ball along the surface of the drum 64 parallel to its axis. Yoke 75 has a lower extension 76 with a threaded end 77 carrying upper lock nuts 78 and lower lock nuts 79 for the purposes herein-after described, and a tension spring 80 biasing the yoke downwardly. The yoke 75 also has an upper extension 83 connected to the control device 84.

Electrically operated solenoids 100, 101, 102 and 103 control the positioning of the ball 63 of the variable speed and direction changing device 57 through the cross tree 110 and the whiffle trees 105, 106. Solenoids 102 and 103 having a reduced stroke set the drive for slow speed which includes the printing rate. The adjusting shaft 115 adjusts the final position of plunger 122 of solenoid 102 to adjust the number of lines per inch which the machine prints. Adjusting screws 100a, 100b and 100c are provided respectively for solenoids 100, 101 and 103. These screws are adjusted at the factory and require no further adjustment.

The operation of each solenoid for each function is described in connection with Figure 11.

If either the plunger 120 of solenoid 100 or the plunger 121 of solenoid 101 (but not both) is re-tracted at the same time as either plunger 122 of solenoid 102 or plunger 123 of solenoid 103 (but not both), the mechanism is adjusted to be in neutral. Picking up one more plunger, say plunger 122, results in causing the drum 11 to rise slowly. At the end of the printing cycle, solenoid 100 is operated to raise plunger 120 forcing drum 11 to move to the end of its scanning movement very rapidly. Also, solenoid 102 is de-energized dropping plunger 122. This is done by transmitting to the printer from the transmitter a tone signal especially intended to pick up the plunger 120 and drop plunger 122 at the will of the transmitting operator. Stops 119 limit the downward movement of each plunger. Plungers 120 and 122 are slotted at 120a and 122a to permit cross trees 105 and 106 to operate over the pre-scribed stroke without binding.

The means for actuating the plungers and the control mechanism therefor, as well as the specific operations of the plungers for each step, is herein-after described.

When the drum 11 reaches the extreme end of its stroke, the nut 130 at its lower end (see Figure 1 as well as Figure 5) binds at the expanded end 13a of the splined shaft 13 inside the drum 11 and rotates the splined shaft 13. As will be clear from Figures 1 and 5, splined shaft 13 has a lower extension 13b of narrower width than the splined shaft 13 and extending through a longitudinal opening in the threaded shaft 12, and the lower bearing 12a of the threaded shaft 12 and through gear 56 to the gear 20.

Consequently when the nut 130 binds on the expanded end 13a of the splined shaft 13, it rotates the splined shaft 13 and its extension 13b to rotate the gear 20 at the lower end and thus to rotate the gear 95 against the bias of the tension spring 23. Stops 24 and 25 separate, thus opening solenoid 101, thus returning the drive mechanism ratio 57 to slow speed to complete the one more turn necessary to unload the paper on drum 11. At the completion of this turn, solenoid 102

is de-energized, dropping plunger 122 to return the mechanism 57 to neutral. This rotation of drum 11 results in releasing the clamp on the paper wound on the drum 11 substantially in the manner herein-after described and discharging the paper through the slot 135 in the upper cylinder 35 into the paper receiving magazine 136 of Figure 9. A feed-out roller 140 serves to draw the paper out rapidly from the cylinder 35 into the magazine 136.

A new sheet may then be fed into the clamp slot and means may then be provided such as passing the new sheet between a pair of normally closed pilot contacts to de-energize the solenoid 103 as the sheet enters the drum. De-energization of solenoid 103, Figure 5, releases the plunger 123 permitting the right-hand end of the whiffle tree 106 to drop and thus permitting the cross tree 119 to drop so that the ball 63 drops slightly below center to slowly rotate the drum 11 while it is at the upper end of its travel with the nut 130 caught on the splined shaft 13 and to slowly feed the new sheet of paper around the drum 11.

At the completion of one such reverse rotation of the drum 11, stops 24 and 25 engage and solenoid 101 would be energized once more to lift the armature 121 were it not for the fact that the paper now loaded on the drum has passed out from between the pilot contacts, thus energizing solenoid 103 and lifting plunger 123, in the manner described in connection with Figure 11.

This drops the left-hand end of the cross tree 110 to a lower position (since armatures 120 and 121 have a longer stroke than armatures 122 and 123) and causes a continuing reverse, very rapid rotation of drum 11 to lower it quickly to its lower-most position. As the drum 11 approaches the lower end of its travel, nut 14 binds on the shoulder 13a of the splined shaft 13 and since the splined shaft 13 is now not able to rotate in that direction owing to the engagement of stops 24 and 25, the nut 14 carries the splined shaft bodily downward thus forcing ball 63 into its neutral position limiting its travel.

The mechanism which forces the ball 63 up into its neutral position comprises the arm 140 pivotally mounted on the stationary pin 141 and having a yoke 142 engaging around the lower end 13b of the shaft 13 between the gear 20 secured thereto and the collar 144. The shaft 13-13b is ordinarily biased in an upward position by the compression spring 145. Consequently any vertical movement of the shaft 13-13b will result in rotation of the arm 140 around its pivot 141. The arm 140 has, at its end opposite the yoke 142, another yoke 150 engaging around the threaded extension 77 under the lock nuts 78 (Figure 5). Consequently when the shaft 13-13b is forced down, the underface of gear 20 will force down yoke 142 of arm 140 thereby raising the yoke 150 pushing up against the lock nut 78 on the extension 76 of the yoke 75 which carries the ball 63 and will thus restore the ball 63 to neutral position thereby stopping the motion of the drum 11.

Arm 140 is provided with extension 137 having an opening through which link 138 passes terminating in head 138a. Link 138 is slidably supported in member 138a and has an upward extension 139 disposed in the path of movement of member 95. On rotation of gear 20 resulting in rotation of gear segment member 95, the side of member 95 will strike extension 139 drawing link 138 to the left and rotating arm 140 counter-clockwise to move end 150 thereof down against nut 79. This will draw down yoke 75 and replace

ball 63 at the neutral position to stop rotation of the drum 11 at exactly the right angular position for feed out and reloading of paper.

The tension of spring 89 and the force of magnets 102-103 are such that a force operating on the yoke 150 of arm 140 through the adjusting nuts 78 and 79 will re-center the ball 63 through either side with quick facility. As above pointed out, the hollow cylinder or drum 35 is stationary and slotted lengthwise at 135 to eject and load the sheets on the drum 11.

The shell 30 rotates continuously and is synchronized and phased in the manner shown in application Serial No. 567,022. The printing motors 32, as above described, are carried on the annular disc 36 (Figures 1 and 2) which is secured in any suitable manner to the rotating cylinder 30. The rotating cylinder 30 is steadied at its upper end by rollers 30c on plate 223 bearing against ring 30d on the cylinder 30. Each printing motor as seen in Figure 2 is provided with a pair of stationary bearing plates 209, 201 secured in any suitable manner as by the bolts 202, 203 to the plate 36. The entire printing motor casing 205 comprises a cylindrical wall having the end plates 205 and 207, the said casing 205-206-207 being rotatably mounted in appropriate bearings in the stationary plates 200-201.

The front plate 207 of the rotatable housing has secured thereto in any suitable manner, as for instance by the bolts 210 and 211, the circular gear 215. The gear extends through the slot 216 in plate 36 and meshes with the stationary annular rack 218 on the stationary annular platform 220 secured in any suitable manner to the main housing 40. Consequently as the rotatable cylinder 30 and the plate 36 rotates, the engagement of gear 215 with the stationary rack 218 results in constant rotation of the printing motor casing 205 and its end plates 206 and 207.

The armature assembly which actuates the pencil 230 in cooperation with the paper on the recording drum 11 is shown more specifically in the expanded views of Figures 3 and 4, which views must be taken together with Figure 2.

The actuating mechanism comprises a stationary magnet core shell 235, the rear end of which is turned down and threaded at 236 and is further turned down at 237. The threaded portion 236 of the magnet core 235 is secured in the tapped opening 239 of the rear plate 206 of the rotatable motor casing. The tubular extension 237 extends out beyond the rear end of the plate 206. A compression spring 240 is mounted over the end of the tubular extension 237 of magnet core 235 and a heel bearing 241 is mounted over the said tubular member 237 bearing against spring 240.

A lead re-set clamp pull bushing 242 is also mounted over the end of the tubular extension 237 and is press-fit into the larger opening 241a of the heel bearing 241, and is maintained in angular alignment with member 235 by the key 242a extending inwardly from the interior of member 242 and engaging with the keyway 237a in member 237. The pencil clamp member or the lead re-set clamp core 250 is threaded at its rear end at 251 and is received in the tapped opening 252 of the bushing 242. A lock nut 253 may be secured to the portion of the threaded end 251 which projects rearwardly of the tapped opening 252.

The heel bearing 241 is received in the counterbore recess 255 of the lead re-set gear 256, the said lead re-set gear 256 having a threaded

5 8 stub shaft 257 which is received in the tapped opening 258 of the plate 200.

Thus, the entire pencil motor and its casing rotates with respect to the plate 200 by reason of the fact that the rearwardly projecting portion 251 of the lead clamp 250 is held by the member 242 which rides in the bearing 241. Annular slip rings 260 are secured to the back plate 206 of the casing being spaced therefrom by the insulating slip ring washer 261.

One of the slip rings 260 on each motor is connected to ground. A suitable brush connection between the other slip ring 260 is made to one of the circular slip rings 263 on the rotating cylinder 30 and current is led to the specific circular slip ring 263 from the stationary brush assembly 264. A slip ring 263 and brush 264 is provided for each of the four pencil motors.

20 The driving coil 275 which is energized in accordance with the variations in the particular color being recorded by the specific pencil motor and which is accordingly connected to the slip ring 260, is wound around the driving coil shell 270. Shell 270 has openings 270b to decrease its 25 weight. The said driving coil shell 270 is mounted on and encases the magnet core 235. The front plate 207 is provided with an opening 272 which receives the front end 273 of the magnet core. Plate 207 is thus one pole of the magnet and end 273 of core 235 is the other pole of the magnet.

30 The coil 275 wound around the shell 270 is wound in the groove 275a (see also Figure 4) and variations in the energization of the coil at 275 result in corresponding motion of the armature or coil-carrying shell 270 resulting in variation of pressure of the pencil 230 on the sheet on the recording drum 11.

The rotatable cylinder 30 is carried up at 39a 40 above the level of the annular rotatable plate 36 and almost up to abutment with the stationary cylinder 35 to protect the sheet on the drum 11 from dust. An opening 306 may be provided in the sleeve or extension 30a to permit the pencil 230 45 to project therethrough into engagement with the sheet on cylinder 11. Small areas between holes 306 may be cut away to permit visual observation of the character of recording; and suitable openings 49a in outer housing 40 may be provided for this purpose. These openings may be filled with transparent material, if desired.

50 The pencil 230 is so arranged that on pressure of varying degrees toward the sheet on the drum 11, it will make marks of varying degrees of shading—the greatest pressure producing the darkest mark and lighter pressure producing intermediate shading.

55 Normally the pencil 230 is held by the armature shell 270 and its associated elements, so that it is just barely in engagement with the sheet on the recording drum 11 but with insufficient pressure to mark the same.

60 Assuming that the pencil of the particular pencil motor of Figure 2 is colored red, then whenever a signal is received for a particular shade of red at the transmitter, the pencil 230 will be forced toward the paper at that instant with a degree of pressure corresponding to the energy of the signal received which in turn corresponds to the darkness of the red at the transmitter. By superimposing red, blue and yellow colored pencil marks on top of each other, a correct reproduction of the particular colors at the transmitter may be obtained.

The fourth black pencil will serve to receive and record from dark markings or black outlinings which may not be recording with proper blackness by the super-position of the red, blue and yellow. The black adds depth to the picture and makes the contrast greater.

Obviously, as above described, when a white area is being transmitted, no energy will be received on any of the pencil motors and none of the pencils will be urged toward the paper.

The front of the pencil motor casing is provided with a conical housing 290 having an extension 291 riding in the bearing 292 supported by the front stationary support 261 so that the entire pencil motor casing rotates on the elements 291 and 242 in the respective opposite bearings 292 and 241.

The lead nose clamp core 310 (Figure 4) is held in the bushing 315, the neck 316 of which projects through the tubular extension 317 of the shell 270.

The pencil clamp which integrates the pencil 230 with the armature shell 270 comprises a tube 250 having a flared forward end 300 which is received in the socket 302 having the flared opening 301. The socket 302 is secured in any suitable manner in the recess 303 of the magnet core 235.

Ledge 322 of bushing 315 bears against the flange 236 of the shell 270. Surface 318 of bushing 315 bears against the inside of tubular extension 317; and the right hand end of tubular extension 317 (Figure 4) is spun over the right end of surface 318 to hold bushing 315 in place.

The end 325 of split nose clamp 310 is even with the left end of bushing 315. The nose clamp 310 is split so that when the parts are allowed to separate, the pencil may slide readily with respect thereto but when they are held tightly together, the pencil is effectively clamped with respect thereto.

Spring 311 provides initial clamping pressure; the dimensioning of bushing 315 and clamp 310 furnishes the remainder of the pressure as needed. The clamping pressure of spring 311 is obtained by reason of the fact that spring 311 bears against the ledge 325 of the clamping nose 310 on one end and against the ledge 330 of the bushing 315 at its front end. This drives the flared end of clamp 310 into the flared end of extension 316 of bushing 315 and causes the clamp 310 to engage pencil 230.

For ordinary recording and in order to maintain the pencil 230 sufficiently sharp, the pencil motor casing 295 containing all of the pencil motor elements revolves continuously on its own axis as it is whirled by the plate 36 around the axis of the drum 11.

When by reason of this continuous sharpening, the pencil 230 is shortened somewhat, then rotation of gear 256 in an appropriate direction will serve to re-set the pencil. This rotation need only be for a fraction of a turn of the gear 256.

It will be seen that when the gear 256 is thus rotated, the threaded end 257 thereof by reason of its engagement with threaded opening 258 of the plate 200 will move outwardly. The guide 250 is pulled to the left with respect to Figures 2 and 3, thus squeezing the flared end 300 into the insert 302. This pinches the segments of the "pin vise" arrangement 300 on to the lead which is inside it. Thus locked, the lead cannot move either to the right or to the left.

A sharp passage of reverse current is then passed through coil 275 which forces the shell 270 to the left. The friction of the lead and the split vise 310 tends to prevent the split vise 310 from moving to the left with the pencil lead 230. The relative motion between the split vise 310 and member 316 then relieves the pinching action of the two halves of the split vise 310 on the lead by reason of the action of spring 311 and the flared end of member 310; so that when the shell 270 moves, it slides the segments 310 along the clamped lead until it strikes its mechanical stop against the end plate 206. When it stops, the current is interrupted; the vise 310 is at a new location on the lead. The gear 256 is returned to its original position releasing the vise 250-300 and permitting printing to resume.

The means for operating the gear 256 is shown schematically in Figure 8 wherein each motor 32 has associated therewith on the plate 36 alongside the motor a magnet 150 having the plunger 151. Plunger 151 is pivotally connected at 152 to the link 153 which is pivotally mounted on the pivot 154. Link 153 is provided with a slot 155 engaging a pin 156 on the rack 157 which is in engagement with the underside of the gear 256.

A compression spring 160 connected at one end to the rack 157 and at the other end to a stationary lug 161 on the plate 36 biases the rack to the left with respect to the bottom motor of Figure 8.

When the magnets 150 of each of the motors is energized, these magnets attract the armature or plunger 151 and rotate the link 153 to drive the rack in a direction to compress the spring. This results in rotation of the gear 256. When the magnet 150 is de-energized, the compression spring 160 drives the elements back to the position shown.

Magnets 150 may be energized from a suitable slip-ring and brush arrangement and may be simultaneously energized from a single connection, or if desired, they may be arranged to be individually energized.

The rack 157 may be mounted in any suitable support, as for instance the supporting member 165 shown in Figure 2. Supporting member 165 may be mounted on the back plate 200 as shown, or on the base plate 36. The magnet 150 is, however, mounted on the annular base plate 36.

The magnets 150 may be energized from time to time either by the receiver operator to re-set the pencils in accordance with visual observation, or a switch may be closed at the end or top of movement of drum 11 to energize the magnets momentarily at the completion of recording, or the magnets may be energized pursuant to an appropriate signal received from the transmitter. Likewise, appropriate switches may be arranged operating at the same angular position as the paper clamp hereinafter described to successively energize and de-energize the magnets as they pass the margin so that the pencil re-set occurs in the margin.

I have found that even when solidly recording a particular color through an entire scanning operation, the pencil is not worn down sufficiently to interfere seriously with recording and accordingly a re-setting operation for the pencil at the completion of each picture is generally sufficient.

In Figures 6 and 7 we have shown a pantograph mounting supporting the armature shell 270 so that it will always be supported and need not slide frictionally on the magnet core 235

while at the same time it may move rectilinearly. The back plate 206 of the printing motor is provided with a plurality of studs 400 projecting normally thereto toward the front of the printing motor and with a plurality of hinge carrying studs 401 also extending normally thereto. Each of the studs 401 carries hingedly connected thereto two pantograph arms 402.

Each pantograph arm 402 is hingedly connected at 405 to the armature shell 270. All of this is apparent from an inspection of Figure 7. As shown in Figure 6, the pantograph arm 402 is supported from each of the studs 401 at a point adjacent the back plate 206 and at a point near the forward end of the armature shell 270. Consequently the armature shell is free to move rectilinearly pursuant to received impulses.

The springs 407 are connected front and back between each stud 400 and the pantograph arms 402. These springs serve to keep the pins of pantograph arms 402 in contact with small recesses or openings in shell 270 and stud 401 as the armature shell is moved back and forth swinging the arms 402 back and forth.

In Figure 8 we have shown a top view taken along lines 8-8 of Figure 1 looking in the direction of the arrows and showing the various printing motor assemblies mounted on the rotatable annular plate 36. From this view it will be seen that the pencils 230 are arranged so that they are not radial of the drum 11 but rather so that they are at an angle to a tangent thereof so that the lead is off-set in the direction of rotation as described in said application Serial No. 567,022. The constant rotation of the printing motors 32 by the gears 215 thus results in continuous sharpening of the pencils 230 in the manner disclosed in the aforementioned application Serial No. 567,022. Thus, the pencils are continuously sharpening during scanning and at the conclusion of the scanning operation or at other intervals as above pointed out are re-set to compensate for any wear.

In Figure 9 we have shown a paper feed device arranged to cooperate with the drum 11 which in turn is more clearly shown in Figures 1 and 10. The drum 11 is shown end on in Figure 9 and in cross-section in Figure 10. It is provided with a clamp 500 which when it is in the position of Figure 10 is perfectly continuous with the surface of the drum 11; but which may be raised as shown in Figure 9 to receive the sheet.

As seen in Figure 10, clamp 500 has secured thereto in any suitable manner a pair of bolts 502 preferably adjacent each end of the drum, which bolts are in turn connected to the slides 503, each of the slides having a longitudinal oval opening 504 surrounding the splined shaft 13. A compression spring 508 surrounds each bolt and is compressed between the surface 509 of the slide 503 and the inner circumference of the drum 11, thus biasing the clamp 500 into clamping position.

A shaft 505 is carried between the ends of the drums and the upper portion of this shaft 505 is provided externally of the end of the drum with the crank arm 506 (Figs. 1 and 8). Shaft 505 within the drum carries crank arms 507 keyed to the shaft in any suitable manner, said crank arms 507 bearing against the extensions 507a of the slide 503. Rotation of crank 506 will rotate the shaft 505 to rotate the arms 507 against the extensions 507a of the slide 503 and drive the slide toward the perimeter of the drum (upwardly with respect to Figure 10) to move the clamp 500 out to disengaged position.

When the crank arm 506 is released, compression spring 508 will drive slide 503 back to the original position shown in Figure 10 re-engaging the clamp 500.

A stationary pin 506a (Figure 1) mounted in the top of upper drum housing 35 will engage crank arm 506 when the drum 11 is rotated to discharge position and release the clamp. On initial return movement of drum 11, the clamp closes. The clamp should be sufficiently deep so that rotation of drum 11 to close the clamp will not cause the clamp to leave the edge of the paper before it engages the paper.

At the completion of the rise of the drum, the rotation of the drum 11 previously described (clockwise as indicated by the arrow 513 of Figure 9), feeds the edge of the sheet out through the slot 135 of the outer cylinder 35 and through the passage 515 to the delivery roll 525 which is a driven roll and idler 140 which feed the recorded sheet into the receiver tray 136. Idler 140 is not driven to avoid smearing the recording. On completion of this clockwise rotation, members 506 and 506a cooperate to open the clamp 500 as previously pointed out.

At the completion of the delivery operation, feed roll 520 which was in an upper position on its arm 520a is lowered and is operated to lift the edge 521 of the sheet 522 from the stack 523. As soon as the edge 521 is raised by the feed roll 520 it snaps to the top side of the feed roll 520, feed roll 520 is raised, and the sheet is fed between the feed roll 520 and the roll 525 up passage 526 until its leading edge enters beneath the clamp 500. Passage 526 is widened to permit the paper to buckle since the drum 11 rotates back more slowly than the speed imparted to the sheet by rolls 520-525. The clamp is then dropped by lowering of slide 503 and on rotation of drum 11 once in the direction opposite to the arrow 513, the paper is wound around the drum 11.

The drum 11 may then be dropped to repeat the scanning operation as previously described. The stack of paper 523 rests against the side member 530, the humped portion 531 of which is biased outwardly by compression spring 532 bearing against side wall 530a, and the upper sheet of the stack is confined in position by the flanges 533 and 534 so that the appropriate portion of the uppermost sheet may be acted on by feed roll 520 while all of the sheets are retained in proper position by the side walls 536 and 537 of the housing.

A pair of pilot switch contacts 550 are provided in the passage 526. These contacts are separated by the paper as it moves up the passage and when separated start the drum 11 rotating to wind up the paper around the drum.

While we have described the operation of our device generally (in connection with Figure 5) as using four solenoids 100, 101, 102 and 103, actually solenoids 102 and 103 are energized simultaneously for all purposes and thus may be connected in parallel to act together.

Or, preferably solenoid 103 may be omitted altogether and solenoid 102 may be spaced farther away from solenoids 100 and 101 by enough to double the length of the cross tree on its side. Thus, the plunger 122 of solenoid 102 may be connected directly to pin 122a of cross tree 110, and the length of the cross tree on that side of rod 83 may be double the length of the cross tree on the opposite side. The forces applied to the ball yoke will thus be equal for all magnets.

Referring to Figure 11, the sequence of operations of the plungers 120, 121, 122 therein shown (for solenoids 100, 101, 102 respectively) is as follows:

Sequence	Operation	Plunger Condition			Remarks
		120	121	122	
1	Idling	Down	Up	Down	Mechanism Stopped.
2	Printing	D	U	U	Signal from Transmitter.
3	Unloading	U	U	U	Do.
4	Paper Discharge	D	U	U	Mechanism Stopped after one revolution of drum.
5	Completion of 4	D	U	U	Mechanism Stopped.
6	Reloading	D	D	D	Entering Paper Initiates Operation of one reverse revolution of drum.
7	Completion of 6	D	D	D	Mechanism Stopped.
8	Drum Reset	D	U	D	Mechanism Stopped.

The operation is as follows:

At sequence 1, the drum is in the downmost position with the mechanical stop holding it in the idling position. When an appropriate signal is received from the transmitting station, relay 505 is energized thus attracting its armature 605, and closing contacts 905, and 705. This closes the circuit through coils 102 and 502 (which are permanently connected in parallel), and lifting plunger 122. Relay 502 seals itself closed by attracting armature 602 and closing contacts 702, and 902 which parallel the connections closed by relay 505.

Relay 505 may now be de-energized without interrupting the operations which follow. During this phase of the operating cycle, contacts 550 have been closed. The consequence of this condition is to throw the speed changing and reversing device which will be referred to simply as the "transmission" into slow speed upward, the exact speed being determined by the adjustment of the adjustable plunger stop 115 which controls the number of printed lines per inch of paper as already described.

After sufficient time has elapsed to have printed an entire page of material or at an earlier time at the discretion of the transmitter operator, a signal is transmitted to the printed to "unload." This signal closes relay 504 by energizing its coil and attracting armature 604 and closing contacts 904, and 704. This operation energizes solenoid 100 and relay 500a, which like relay 502 seals itself by attracting armature 603 to close contacts 900, and 700. At this time contacts 708 and 908 operated by gear segment 95 are also in contact having been closed at sequence 7.

The reception of the "unload" signal is sequence 3.

The consequence is that the transmission is thrown into high speed upward, which reduces the unloading time over that required had the drum continued to progress upward at the printing rate. When it has reached its most extreme top position, the advance screw 12 locks with the splined shaft 13 and rotates the drum 11 in such a direction to feed off the paper which is on it into the discharge magazine.

When drum 11 starts to rotate, contacts 708 and 908 separate de-energizing relay 500 and solenoid 100 and dropping the plunger 120. This returns the transmission to low speed upward for the remainder of the drum revolution.

The opening of contacts 708 and 908 constitute sequence 4.

The completion of one turn of the drum 11 and the arresting of any further rotation by the mechanical stopping mechanism in the transmission is sequence 5. At this time the rollers 520—525 in the paper storage magazine thread a new

sheet into position to be loaded onto the drum. As the leading edge is about to enter the retaining slot in the drum, it passes between contacts 550 breaking their circuit.

This is sequence 6.

It results in the de-energizing of solenoid 102 and relay 502 in addition to solenoid 101 and relay 501. Now all solenoids and relays are open and all plungers are down and the transmission is in high speed down. The drum quickly turns one revolution thus drawing around itself the new sheet of paper. When it has completed this turn the contacts 708 and 908 reclose as gear segment 95 returns to its original position, and also prevents any further rotation of the drum. The lead screw 12 which must continue to rotate then proceeds to crank down the cylinder to its lower-most position in place to begin printing a new facsimile.

The reclosing of contacts 708 and 908 constitute sequence 7.

This event does not initiate any activity or alter any condition which already exists. When the drum reaches the end of its downward stroke, contacts 906 and 706 are closed by bridging contact 506c when the mechanical neutralizing lever 140 begins to come into play to stop the further travel.

This is sequence 8.

At this time relay 501 and solenoid 101 are energized and sealed by armature 601 and the closing of contacts 701 and 901. Plunger 121 is lifted thus throwing the transmission into slow speed down, which continues until the mechanical stop terminates the downward travel.

It is then in sequence 1 again until further notice.

50 A further simplification may be followed by eliminating solenoid 101 and relay 501 along with contacting mechanism 506c, thus relying completely on the mechanical stop to bring the device to rest at the lower limit. The remaining 55 sequence would be unaltered. The cross tree 110 would again be fulcrummed at the center and whiffle trees 105 and 106 would not be needed.

In sequence 1 the transmission is in neutral. 60 If it is left in that condition very long, excessive wear may take place at the center of the drive disc 68. To prevent this, the spring washer 71 may be replaced by a magnet which would work through the disc thrust bearing to be energized 65 at sequence 2, would seal itself in, similar to relays 500 and 502, and be de-energized at sequence 8 by a series contact similar to mechanism 506c but inverted so as to be opened instead of closed at sequence 8 as does 506c. This would also obviate the mechanical neutralizing device 140 on the transmission needed for the lower end of the drum stroke.

By means of the foregoing, it thus becomes possible to make an instantaneous recording of 75 a color facsimile image without the necessity for

complex photographic developing operations and accurate matching of color separation negatives. My facsimile receiver is entirely automatic in operation. The user need only load the paper magazine of Figure 9 and remove the completed facsimile sheet as it is delivered from the drum. He need perform no other operations with respect to the device.

Accordingly, my invention is adapted for use by the unskilled home user as well as by technical personnel but need not be put to the trouble of operating any of the mechanism or to the further trouble of developing and printing photographic separation negatives or positives and matching them up.

In the foregoing I have described my invention solely in connection with a specific illustrative embodiment thereof. Since many variations and modifications will now be obvious to those skilled in the art, I prefer to be bound not by the specific disclosures herein but only by the appended claims.

I claim:

1. In a facsimile receiver for recording a color image on a record sheet; means for supporting the record sheet; a plurality of record marking means; means for causing relative longitudinal movement between said record supporting means and said record marking means; means for causing relative rotational movement between said record supporting means and said record marking means; each of said record marking means including a marking member in engagement with the surface of the record sheet; and means for varying the pressure of each marking member in accordance with variations in the elemental shading of the image being recorded to vary the density of the mark on the record sheet.

2. In a facsimile receiver for recording a color image on a record sheet; means for supporting the record sheet; a plurality of record marking means; means for causing relative longitudinal movement between said record supporting means and said record marking means; means for causing relative rotational movement between said record supporting means and said record marking means; each of said record marking means including a marking member in engagement with the surface of the record sheet; each marking member being adapted on variation of pressure to make a mark on the record sheet having a density corresponding to the pressure thereon and each marking member being adapted to make a mark of a color different from that of the other marking members; and means for varying the pressure of each marking member in accordance with variations in the elemental shading of the image being recorded.

3. In a facsimile receiver for recording a color image on a record sheet; means for supporting the record sheet; a plurality of record marking means; means for causing relative longitudinal movement between said record supporting means and said record marking means; means for causing relative rotational movement between said record supporting means and said record marking means; each of said record marking means including a marking member in engagement with the surface of the record sheet; each marking member being adapted on variation of pressure to make a mark on the record sheet having a density corresponding to the pressure thereon and each marking member being adapted to make a mark of a color different from that of the other marking members; and means for

varying the pressure of each marking member in accordance with variations in the elemental shading in the image being recorded of the particular color which that marking member is adapted to record.

4. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a marking member in engagement with the surface of the record sheet; and means for varying the pressure of each marking member in accordance with variations in the elemental shading of the image being recorded to vary the density of the mark on the record sheet.

5. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a marking member directed substantially toward the center of said rotatable member; said drum being positioned at the center of rotation of said rotatable member; each marking member engaging the surface of the record sheet; and means for varying the pressure of each marking member in accordance with variations in the elemental shading of the image being recorded to vary the density of the mark on the record sheet.

6. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a marking member directed substantially toward the center of said rotatable member; said drum being positioned at the center of rotation of said rotatable member; each marking member engaging the surface of the record sheet at an angle to a tangent of the drum; and means for varying the pressure of each marking member in accordance with variations in the elemental shading of the image being recorded to vary the density of the mark on the record sheet.

7. In a facsimile receiver for recording a color image on a record sheet; means for supporting the record sheet; a plurality of record marking means; means for causing relative longitudinal movement between said record supporting means and said record marking means; means for causing relative rotational movement between said record supporting means and said record marking means; each of said record marking means including a pencil in engagement with the surface of the record sheet; and means for varying the pressure of each pencil in accordance with variations in the elemental shading of the image being recorded to vary the density of the mark on the record sheet.

8. In a facsimile receiver for recording a color image on a record sheet; means for supporting the record sheet; a plurality of record marking means; means for causing relative longitudinal movement between said record supporting means

and said record marking means; means for causing relative rotational movement between said record supporting means and said record marking means; each of said record marking means including a pencil in engagement with the surface of the record sheet; and means for varying the pressure of each pencil in accordance with variations in the elemental shading of the image being recorded to vary the density of the mark on the record sheet, each record marking means carrying a pencil of a different color.

9. In a facsimile receiver for recording a color image on a record sheet; means for supporting the record sheet; at least three record marking means; means for causing relative longitudinal movement between said record supporting means and said record marking means; means for causing relative rotational movement between said record supporting means and said record marking means; each of said record marking means including a pencil in engagement with the surface of the record sheet; and means for varying the pressure of each pencil in accordance with variations in the elemental shading of the image being recorded to vary the density of the mark on the record sheet, each record marking means carrying a pencil of a different color, the pencils for said record marking means being respectively red, blue and yellow in color.

10. In a facsimile receiver for recording a color image on a record sheet; means for supporting the record sheet; at least four record marking means; means for causing relative longitudinal movement between said record supporting means and said record marking means; means for causing relative rotational movement between said record supporting means and said record marking means; each of said record marking means including a pencil in engagement with the surface of the record sheet; and means for varying the pressure of each pencil in accordance with variations in the elemental shading of the image being recorded to vary the density of the mark on the record sheet, each record marking means carrying a pencil of a different color, the pencils of said record marking means being respectively red, blue, yellow and black.

11. In a facsimile receiver for recording a color image on a record sheet; means for supporting the record sheet; a plurality of record marking means; means for causing relative longitudinal movement between said record supporting means and said record marking means; means for causing relative rotational movement between said record supporting means and said record marking means; each of said record marking means including a pencil in engagement with the surface of the record sheet; and means for varying the pressure of each pencil in accordance with variations in the elemental shading of the image being recorded to vary the density of the mark on the record sheet, one of said pencils being black.

12. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a pencil in engagement with the surface of the record sheet; and means for varying the pressure of each pencil in accordance with variations in the elemental shading

of the image being recorded to vary the density of the mark on the record sheet, each record marking means carrying a pencil of a different color.

5. 13. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a pencil in engagement with the surface of the record sheet; means for varying the pressure of each pencil in accordance with variations in the elemental shading of the image being recorded to vary the density of the mark on the record sheet, each record marking means carrying a pencil of a different color; and means operable on rotation of said rotatable member to continuously rotate said pencils on their respective axes to sharpen the same.

25. 14. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a pencil in engagement with the surface of the record sheet; means for varying the pressure of each pencil in accordance with variations in the elemental shading of the image being recorded to vary the density of the mark on the record sheet, each record marking means carrying a pencil of a different color; means operable on rotation of said rotatable member to continuously rotate said pencils on their respective axes to sharpen the same; and means for periodically advancing each pencil toward the paper.

35. 15. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a pencil in engagement with the surface of the record sheet; and means for varying the pressure of each pencil in accordance with variations in the elemental shading of the image being recorded to vary the density of the mark on the record sheet, each record marking means carrying a pencil of a different color, said last mentioned means including a rotatable mounting for each pencil on said rotatable member; a gear on said rotatable mounting; and a stationary gear meshing with said gear on said rotatable mounting.

45. 16. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a pencil in engagement with the surface of the record sheet; means for varying the pressure of each pencil in accordance with variations in the elemental shading of the image being recorded to vary the density of the mark on the

record sheet, each record marking means carrying a pencil of a different color; means operable on rotation of said rotatable member to continuously rotate said pencils on their respective axes to sharpen the same; and means for periodically advancing each pencil toward the paper, said last mentioned means including a clamp for each pencil, a member operable on movement in one direction to release said clamp and advance said pencil and operable on return movement to reengage said clamp.

17. In a facsimile receiver for recording a color image on a record sheet; means for supporting the record sheet; a plurality of record marking means; means for causing relative longitudinal movement between said record supporting means and said record marking means; means for causing relative rotational movement between said record supporting means and said record marking means; each of said record marking means including a pencil in engagement with the surface of the record sheet; and means for varying the pressure of each pencil in accordance with variations in the elemental shading of the image being recorded to vary the density of the mark on the record sheet, said last mentioned means including a magnet and armature individual to each pencil; a clamp connecting said pencil to said armature for movement therewith.

18. In a facsimile receiver for recording a color image on a record sheet; means for supporting the record sheet; a plurality of record marking means; means for causing relative longitudinal movement between said record supporting means and said record marking means; means for causing relative rotational movement between said record supporting means and said record marking means; each of said record marking means including a pencil in engagement with the surface of the record sheet; means for varying the pressure of each pencil in accordance with variations in the elemental shading of the image being recorded to vary the density of the mark on the record sheet, said last mentioned means including a magnet and armature individual to each pencil; a clamp connecting said pencil to said armature for movement therewith; and means for supporting said armature for free movement with respect to said magnet.

19. In a facsimile receiver for recording a color image on a record sheet; means for supporting the record sheet; a plurality of record marking means; means for causing relative longitudinal movement between said record supporting means and said record marking means; means for causing relative rotational movement between said record supporting means and said record marking means; each of said record marking means including a pencil in engagement with the surface of the record sheet; means for varying the pressure of each pencil in accordance with variations in the elemental shading of the image being recorded to vary the density of the mark on the record sheet, said last mentioned means including a magnet and armature individual to each pencil; a clamp connecting said pencil to said armature for movement therewith; and pantograph means for supporting said armature for free movement with respect to said magnet.

20. In a facsimile receiver for recording a color image on a record sheet; a drum for supporting the record sheet; a plurality of recording marking means; said record marking means being mounted on a rotatable member rotating in a plane normal to the axis of the drum; said drum

being movable along its axis as the rotatable member rotates; each of said record marking means including a marking member in engagement with the surface of the record sheet; means for varying the pressure of each marking member in accordance with variations in the elemental shading of the image being recorded to vary the density of the mark on the record sheet, and releasable record sheet holding means on said drum.

10 21. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a marking member in engagement with the surface of the record sheet; means for varying the pressure of each marking member in accordance with variations in the elemental shading of the image being recorded to vary the density of the mark on the record sheet; releasable record sheet holding means on said drum; and automatic control means for causing said drum to move a scanning speed in the scanning direction and at high speed in the reverse direction.

15 22. In a facsimile receiver for recording a color image on a record sheet; a drum for supporting the record sheet; a plurality of recording marking means; a rotatable member rotating in a plane normal to the axis of said drum, said record marking means being mounted on said rotatable member; said drum being movable along its axis as said rotatable member rotates; each of said record marking means including a marking member in engagement with the surface of the record sheet; means for varying the pressure of each marking member in accordance with variations in the elemental shading of the image being recorded; releasable record sheet holding means on said drum; and automatic control means for causing said drum to move at scanning speed in the scanning direction and at high speed in the reverse direction, said control means also causing said drum to rotate on its axis at the end of the scanning movement to discharge the record sheet and to rotate back prior to re-setting of the drum to wind another record sheet thereon.

20 23. In a facsimile receiver for recording a color image on a record sheet; a drum for supporting the record sheet; a plurality of recording marking means; a rotatable member rotating in a plane normal to the axis of said drum, said record marking means being mounted on said rotatable member; said drum being movable along its axis as the rotatable member rotates; each of said record marking means including a marking member in engagement with the surface of the record sheet; means for varying the pressure of each marking member in accordance with variations in the elemental shading of the image being recorded; releasable record sheet holding means on said drum; and automatic control means for causing said drum to move at scanning speed in the scanning direction and at high speed in the reverse direction, said control means also causing said drum to rotate on its axis at the end of the scanning movement to discharge the record sheet and to rotate back prior to re-setting of the drum to wind another record sheet thereon, said last mentioned operations being performed in response to movement of the drum to complete the scanning operation.

24. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a marking member in engagement with the surface of the record sheet; means for varying the pressure of each marking member in accordance with variations in the elemental shading of the image being recorded to vary the density of the mark on the record sheet; a longitudinal screw for driving said drum; speed and direction changing mechanism connected to said screw.

25. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a marking member in engagement with the surface of the record sheet; means for varying the pressure of each marking member in accordance with variations in the elemental shading of the image being recorded to vary the density of the mark on the record sheet; a longitudinal screw for driving said drum; speed and direction changing mechanism connected to said screw; and automatic control means for causing said drum to move at scanning speed in the scanning direction and at high speed in the reverse direction.

26. In a facsimile receiver for recording a color image on a record sheet; a drum for supporting the record sheet; a plurality of recording marking means; said record marking means being mounted on a rotatable member rotating in a plane normal to the axis of the drum; said drum being movable along its axis as the rotatable member rotates; each of said record marking means including a marking member in engagement with the surface of the record sheet; means for varying the pressure of each marking member in accord-

ance with variations in the elemental shading of the image being recorded to vary the density of the mark on the record sheet; a longitudinal screw for driving said drum; speed and direction changing mechanism connected to said screw; and means responsive to the position of said drum for controlling said speed and direction changing mechanism.

27. In a color facsimile receiver, a recording sheet, a plurality of pencils in engaging contact with the surface of said recording sheet, each of said pencils constructed to leave individual color impressions on said sheet when pressure is applied thereto, means for applying a relative movement between said pencils and said sheet, and means for varying the pressure applied to each of said pencils individually in accordance with a predetermined image to be reproduced.

28. In a color facsimile receiver, a recording sheet, a plurality of pencils in engaging contact with the surface of said recording sheet, each individual to a predetermined color, said pencils being angularly disposed with respect to each other in a plane at right angles to the axis of said drum and adjacent the outer circumference of said drum, each of said pencils constructed to leave individual color impressions on said sheet when pressure is applied thereto, means for applying a relative movement between said pencils and said sheet, and means for varying the pressure applied to each of said pencils individually in accordance with a predetermined image to be reproduced.

LA VERNE R. PHILPOTT.
